THERAPEUTIC AID

Bancroft Hill, Baltimore, Md.

Application March 2, 1950, Serial No. 147,319

2 Claims. (Cl. 65—15)

1

The present device relates to an apparatus for aiding certain handicapped persons who, by some impediment in the use of their body or limbs, are unable to feed themselves. This device is particularly adapted to transferring food from a plate or shallow container to the patient's mouth by the use of the feet. This particular idea is a further development of the general idea as disclosed in my prior application of therapeutic aids.

This apparatus is operable by a person having only one foot available, and the primary object of the invention is to provide a practical and efficient device of this nature by which a person may feed himself from a plate or shallow platter.

Another object is to provide a device which would be simple to operate and economical to make.

With these and other objects in view, certain uses and advantages will become apparent as the nature of the invention is more fully disclosed, and consists in the novel construction, combination and arrangement of parts shown in the accompanying drawings and described in the detailed description forming a part of the specifications in which:

Figure 1 is a top plan view of the apparatus.

Figure 2 is a view in elevation of the same.

Figure 3 is an enlarged fragmentary vertical view of one type of operating arm and means for operating the same.

Figure 4 is a view of a modified form of arm and arm control means.

Figure 5 is a top plan view of the same.

Figure 6 is a fragmentary vertical end view of the preferred form of foot operating mechanism.

Figure 7 is a vertical side view of a modified form of arm operating means therefor.

Figure 8 is a top plan of the same.

Like numerals indicate like and similar parts throughout the several views.

The apparatus consists of a table, or base support, 9, having a standard, or shaft, 10 extending vertically from the upper surface of the top of the table. Slidably positioned on top of the table is a rack 12 having its ends guided by the members 14 and 16 extending at right angles to the rack, the rack being movable in the direction of the arrow 18. Extending at right angles to the frame, or rack, 12 and adapted to operate beneath the rack 12 is a second frame, or rack, 20 which is guided along the table top in the direction of the arrow 22 by the members 24 and 26 which are attached to the rack 20 and

extend over the edge of the table top. The two frames are movable at right angles to each other over the table top. The opening between the frames is always of the same size and is adapted to receive and accommodate a tray, or shallow container, 28. The object of the double slideable frame is to be able to move the tray 28 to any desired location over the table top. Secured to each side of the frame 20 are cords 30 and 32. 5 The cord 32 has one end attached to the rack 20 by means of an eye 34. The cord is carried over a pulley 35 and attached to a weight 36. The cord 30 is attached to the opposite side of the rack 20 by means of the eye 38. The cord is then passed over the pulleys 40, 42 and 44 and down to the pedal 46. Pulleys 35 and 40 are positioned diametrically opposite each other on opposite sides of the table.

10 The rack 12 is moved by cords 48 and 50. One end of the cord 48 is fastened to the rack by the eye member 52 and extends over the pulley 54 and has secured to its opposite end a weight 56. The cord 50 has one end secured to the opposite side of the rack 12 by means of the eye member 58, the opposite end of the cord extending downwardly over the near edge of the table and pulley 60 and pulley 61 to a pedal 62.

15 Associated with the pedal 46 is a weight 64 which, with the weight of the pedal, is substantially equal to the weight 36 attached to the cord 32. The pedals are of the heel and toe operating type as shown best in Figure 6, in which the pedal is pivoted adjacent its center as shown at 68.

20 The rack 20, to which the cords 30 and 32 are attached, is moved to the right by pressing on the toe of the pedal 46 which will overcome the force exerted by the weight 36 and will move the weight 36 upwardly as the rack is moved to the right. When it is desired to move the rack to the left, the heel is pressed raising the toe end of the pedal 46 and the weight 64, which relieves the tension on cord 30 sufficiently to allow the weight 36 to move the rack to the left.

25 A similar action moves the rack 12; when the toe end of the pedal 62 is moved downwardly, the rack is moved toward the operator, or in the direction of the pull by the cord 50. When the toe end of the pedal 62 and the weight 66 are raised by depressing the heel portion 62' of the pedal, the tension on cord 50 is relieved sufficiently to allow the weight 66 to move the rack in the opposite direction, or away from the operator.

30 By these two pedals the racks may be moved to any location over the table top. The arm members of these racks always provide a rectangular

support, or guiding means, for the tray or platter. While it is shown that the opening formed by the cross members of the frames is rectangular in form, it may be of any size or shape depending upon the shape and form of the racks, or the type or shape of the container to be handled.

To facilitate the movement of the frames and obtain greater movement of the frame as compared to the movement of the pedals, for example in Figure 6, the cord 50 may extend downwardly and under a pulley 70 and up to a bracket 72 fastened to the back of the table. This type arrangement will cause the rack to move twice the distance of the pedal, and the bracket 72 will provide means for adjusting the position of the pedal by lengthening or shortening the cord.

In Figure 2, extending upwardly at one side of the horizontally movable racks 12 and 20 is a standard or shaft 10 fixedly secured to the table top. This standard is constructed preferably from a flat strip of metal having a twist, or spiral, preferably of ninety degrees; however, the spiral may be of any predetermined amount to move the arm through any desired arc. Extending outwardly from the standard 10 is an arm 74. The arm 74 is provided with a bearing 75 containing an opening which will slidably fit about the spiral standard which may be moved up the standard by a simple mechanical apparatus and is adapted to be moved downwardly by its own weight. The moving apparatus for the arm 74 consists of an elevating cord indicated by portions 76 and 76'. The elevating cord and the spiral standard are adapted to elevate and rotate the arm as the arm is moved upwardly. One end of the cord 76' extends from an eye member 77 carried by the arm 74, located adjacent the frame 15, upwardly and over a pulley 78 which is supported at the upper end of the standard 10. The cord 76 continues downwardly from the pulley 78 through an aperture 9' in the table to a pulley 79, then horizontally to and over a pulley 53 and downwardly over the pulley 81 to the pedal 82. While the cord is shown to be directly connected to the pedal 82, the cord may be arranged as shown in Figure 6 which was illustrated and described as the preferred form for operating the racks.

Attached to the outer end of the arm 74 is a spoon, fork, or other implement 80 upon which food or other materials may be handled or lifted.

By pressing the toe of the pedal 82, the cord 76 will be drawn downwardly, the portion 76' extending upwardly and over the pulley 78 will draw the arm 74 up the standard 10. By the particular shape of the spiral the arm will first move vertically then be gradually turned outwardly toward the operator as it advances up the standard. The arm is returned by its own weight by gradually releasing the pressure on the toe of the pedal. The weight 67 may be used to help counteract the weight of the arm and materials being carried by the arm.

In operation, the tray or platter 28 is first placed in the opening between the side members of racks 12 and 20 with the desired kind and amount of food for the patient, the implement (or spoon as shown) 80 being positioned adjacent the right side 28' of the tray 28. The patient will sit at the near side of the table facing the pedals 46, 62 and 82 (Figure 2) in order to operate the pedals. By pressing the toe portion of the pedals 62, or the heel portion 62', the tray 28 is moved toward or away from the patient, or from front to rear of the table. By moving the toe of the

pedal 46, the platter may be moved toward the right, and by depressing the heel portion 46' the platter may be moved toward the left by the weight 36. When the platter is moved toward the right and the spoon, or implement, is lowered into the tray, food will be picked up on the implement. When a sufficient amount of food is on the implement, the patient removes his foot and transfers it to pedal 82 and by pressing on the toe portion of the pedal, the arm 74 and the spoon are moved upwardly, and by virtue of the spiral, the arm 74 is swung around to a position where the patient may take the food off the implement, or spoon, by mouth after which the arm is lowered by releasing the pressure on the toe of pedal 82, or by pressing slightly on the heel portion 82' of the pedal. The operation may be repeated to the satisfaction or desire of the patient.

By this apparatus a patient who has had the misfortune of losing the use of all limbs except a single leg and foot may have the satisfaction of feeding himself and at the same time the device will serve as a therapeutic aid to the patient.

In Figure 4 there is shown a modified form of arm and arm rotating means. In this structure, the arm 74 is carried upon a vertical tubular shaft 90 which is likewise fastened perpendicularly to the table top similar to the member 10. The cord 76 is supported on a pulley 91 which is supported on an eccentric arm 90'. Slidably receivable over the tube 90 is a bearing 106 to which the arm 74 is fixedly secured. Extending outwardly and in opposite directions to the arm 74 is a shorter arm 13. There is also a guide member 92 fixed to the table top adjacent the shaft 90. This guide member has a guiding edge or cam surface 92' along which the arm 13 travels when the arm 74 is moved along the tube. There is further provided a steadyng member 93 for holding the arms 13 and 74 more definitely in contact with the guiding edge 92' when the arms are adjacent the table. The pulley 91 is eccentrically positioned on the side of the standard 90 opposite the guide members 92. The end of the cord 76' of the cord 76 is fastened to the arm 74 by the eye member 94 and extends over the pulley 81, through the aperture 9' of the table 9 and around pulley 95 to the bracket 96. The pulley 95 is attached to the pedal 82 and is adapted through the cord 76 to move the arm 74 upwardly when the toe of the pedal is depressed.

The operation of the arm 74 and the spoon 80 in Figure 4 is substantially the same as previously described. It will be noted that by the position of the pulley 91 the cord exerts a swinging action to the arm 74. This causes the arm 13 to be held in contact with the guide edge 92' as the arm 74 is being lifted upwardly by the cord. The action of the guiding edge 92' is to allow the arm 74 to be lifted vertically for a short distance and as the arm continues to be moved upwardly, it will swing around to a point substantially at right angles to its original starting position in order that the patient may take the food in his mouth from the spoon.

Figures 7 and 8 show a further modification of the arm. In this form there is provided a standard 98 and a guiding means in the form of an arm 99 extending outwardly therefrom. To take the place of the arm 74 is a pair of arms 100 and 101 and a pair of end members 102 and 103 which are hingedly secured to the standard 98 at 97 forming a pantograph. One end of the member 100 extends beyond the member 103 as portion 100', and located at the outer end thereof is an

eye member 104 into which one end of the cord 76 is attached. Attached approximately centrally of the arm 101 is a short cord 105 which has its opposite end attached to the outer end of the member 99. The cord 76 is guided through the table top by way of the aperture 9' which is at one side of the standard 98 as shown in Figure 8. When the cord 76 is pulled, there is a tendency to swing the pantograph about the pivot 97, its movement being restrained only by the cord 105. When the pantograph has reached the position shown in dotted lines in Figure 7, the cord 105 extends outwardly and substantially horizontally to its full length, which brings the implement, or spoon 80, to a position approximately ninety degrees from its starting position thereby raising and swinging the spoon to a point where the patient can take the food as described hereinbefore.

While several modifications of the invention have been shown and described in detail, other forms and variations are readily conceivable, and it is not intended that those forms shown should be a limitation of the general principles involved, and the invention is best defined in the appended claims.

I claim:

1. In an apparatus of the character described comprising a table, a pair of adjacent reciprocating racks movable over the top of the table and at right angles to each other, a removable container carried by the said reciprocating racks, each of the said racks having means for engaging the container for locating the same on the table top, an arm reciprocable perpendicular to the table top, having means at one end thereof for engaging a support and guide member for supporting and guiding said arm, said support and guide member adapted to support and automatically rotate the arm horizontally as the same is reciprocated along the support, an implement carried by the opposite end of the arm adapted to be raised and lowered in the said container, foot pedals located beneath the table having

means associated therewith for reciprocating the said racks and a separate foot pedal for reciprocating the said arm.

2. In an apparatus of the character described comprising a table, a movable container located upon the top of the table and means for locating the said container, an arm reciprocable perpendicular to the table top having means at one end thereof for engaging a support and guide member for guiding and swinging the arm horizontally as it is moved along the said support and guide member, said arm support and guide member comprising a vertical spiral shaft positioned above the plane of the table top, a bearing at one end of the arm for engaging the said spiral shaft, an implement carried on the opposite end of the arm adapted to be raised and lowered in the said container, a pair of foot treads for locating the said container and a single foot tread for reciprocating the said arm.
